E. I. DODDS

SHEET STRUCTURE

Filed Dec. 29, 1924

Patented Nov. 15, 1927.

UNITED STATES PATENT OFFICE.

ETHAN I. DODDS, OF CENTRAL VALLEY, NEW YORK, ASSIGNOR TO UNION METAL PRODUCTS COMPANY, OF CHICAGO, ILLINOIS, A CORPORATION OF DELAWARE.

SHEET STRUCTURE.

Application filed December 29, 1924. Serial No. 758,664.

This invention relates to improvements in sheet structures and has particular reference to such as may be employed in car construction, one object of the invention being to provide a sheet metal structure suitable for use as ends, side sheets, floor sheets, door sheets, roof sheets or other car parts, which shall be so corrugated as to insure adequate strength and stability.

10 A further object is to corrugate a sheet for the purpose stated, (whether the sheet be of metal or other material) in such manner that bulging of the sheet shall be avoided and so that the sheet, as a whole, will retain its generally flat form.

15 A further object is to provide a sheet metal or other sheet structure which shall be so corrugated that it will adequately withstand strains to which it may be subjected, and so that warping of the sheet will be obviated.

20 A further object is to provide a metal sheet which shall be so corrugated that the metal of the sheet will not be materially strained or caused to exceed its elastic limit during the operation of corrugating the sheet.

25 With these and other objects in view, the invention consists in certain novel features as hereinafter set forth and pointed out in the claims.

30 In the accompanying drawings:

Fig. 1 shows a sheet embodying my invention.

35 Fig. 2 is a section on line 2—2 of Fig. 1. Fig. 3 is the same as Fig. 2 and shows the corrugations deepest adjacent the center of the sheet.

40 Figs. 4 to 7, inclusive, show modified forms of the invention.

45 In the drawings, I have shown my improvements as applied to a sheet metal car end, but they may be applied to car side, floor, roof or door structures, and may be utilized in the construction of other car parts.

The metallic sheet 1 is reinforced by having a plurality of corrugations or embossments formed therein so interwoven and positioned relative to the center and edges or sides of the sheet structure as to materially increase the strength of the sheet to resist buckling, warping and load stresses. The corrugations are of a general spiral form and are made circular or with straight connected portions as desired and to suit the

shape of the structure or device to be reinforced. The sides or edges of the sheet may be provided with flanges 2 or reinforced in any other convenient manner.

Fig. 4 shows two interwoven spiral corrugations 20—21 as used to reinforce the end wall of a railway box car. Figs. 1 and 2 show two interwoven corrugations 3—4 and 9—10 of general spiral form having straight connected portions which are substantially parallel to the sides of the sheet. Various combinations of the structures shown in Figs. 1 and 4 could be devised and still come within the scope of this invention. The corrugations may be of uniform depth from end to end or they may be made of diminishing depths from the central portion of the sheet to the side edges thereof, as shown in Fig. 3, or the deeper portions of the corrugations may be located at the edge portion instead of at the central portion of the sheet.

Fig. 1 shows two corrugations each having their inner ends positioned near the center of the sheet and each split or divided to form two parallel portions 3—4 or 9—10. The outer ends of these split portions terminate adjacent different corners of the sheet.

Fig. 3 shows the corrugations being deepest adjacent the center of the sheet and diminishing in depth toward the edges of the sheet.

Fig. 5 shows the invention used to reinforce an oblong sheet such as would be used for an end wall of a gondola car or a railway car hopper door. These corrugations 13—14 are of general spiral form.

In Fig. 6, a plurality of angularly formed corrugations 16 are shown and disconnected from each other but, as a whole, provide a generally spiral formation. In Fig. 7, two spiral corrugations 17 and 18 are shown and these are disconnected from each other at the central portion of the sheet.

Having fully described my invention what I claim as new and desire to secure by Letters-Patent, is:

1. A metallic sheet having a plurality of interwoven corrugations formed therein of general spiral form, the inner ends of said corrugations being located near the center of the sheet and the outer ends of said corrugations being located near the edges of the sheet.

2. A metallic sheet having a plurality of interwoven corrugations formed therein of

general spiral form, the inner ends of said corrugations being located near the center of the sheet and the outer ends of said corrugations being located near the edges of the sheet and adjacent opposite corners thereof.

3. A metallic sheet having a plurality of interwoven corrugations formed therein of general spiral form, the inner ends of said corrugations being located near the center of the sheet and the outer ends of said corrugations being located near the edges of the sheet, said corrugations being deepest adjacent the center of the sheet.

13. 4. A metallic sheet having a plurality of interwoven corrugations formed therein of general spiral form, the inner ends of said corrugations being located near the center

20 of the sheet and the outer ends of said corrugations being located near the edges of the sheet, said corrugations being deepest adjacent the center of the sheet and decreasing in depth toward the edges thereof.

5 A metallic sheet having a plurality of

23. A metallic sheet having a plurality of interwoven corrugations formed therein of general spiral form, the inner ends of said corrugations being located near the center of the sheet and the outer ends of said corrugations being located near the edges of the sheet.

sheet and adjacent opposite corners thereof, said corrugations being deepest adjacent the center of the sheet and decreasing in depth toward the edges thereof.

35 6. A metallic sheet having a plurality of interwoven corrugations formed therein of general spiral form including straight portions substantially parallel to the edges of the sheet, the inner ends of said corrugations being located near the center of the sheet
40 and the outer ends of said corrugations being located near the edges of the sheet.

7. A metallic sheet having a plurality of interwoven corrugations formed therein of

general spiral form including straight portions substantially parallel to the edges of the sheet, the inner ends of said corrugations being located near the center of the sheet and the outer ends of said corrugations being located near the edges of the sheet and adjacent opposite corners thereof. 50

8. A metallic sheet having a plurality of interwoven corrugations formed therein of general spiral form including straight portions substantially parallel to the edges of the sheet, the inner ends of said corrugations being located near the center of the sheet and the outer ends of said corrugations being located near the edges of the sheet, said corrugations being deepest adjacent the center of the sheet. 55 60

9. A metallic sheet having a plurality of interwoven corrugations formed therein of general spiral form including straight portions substantially parallel to the edges of the sheet, the inner ends of said corrugations being located near the center of the sheet and the outer ends of said corrugations being located near the edges of the sheet, said corrugations being deepest adjacent the center of the sheet and decreasing in depth toward the edges thereof.

10. A metallic sheet having a plurality of interwoven corrugations formed therein of general spiral form including straight portions substantially parallel to the edges of the sheet, the inner ends of said corrugations being located near the center of the sheet and the outer ends of said corrugations being located near the edges of the sheet and adjacent opposite corners thereof, said corrugations being deepest adjacent the center of the sheet and decreasing in depth toward the edges thereof. 75 80

In testimony whereof, I have signed this specification.

ETHAN I. DODDS.
